UNITED STATES PATENT OFFICE.

JOHN MENAHAN, OF NEW YORK, N. Y.

FASTENER FOR BAGS.

SPECIFICATION forming part of Letters Patent No. 329,192, dated October 27, 1885.

Application filed January 26, 1885. Serial No. 154,031. (No model.)

To all whom it may concern:

Be it known that I, JOHN MENAHAN, a subject of the Queen of Great Britain, residing at New York, county and State of New York, have invented certain new and useful Improvements in Fasteners for Bags, &c., of which the following is a specification.

In a certain class of clasps or fasteners for bags, &c., having a hinged frame at the opening, each part of the frame has rigidly secured to it a knob or handle, which are so arranged as to pass laterally by and partly around each other when the bag is closed, as shown in Letters Patent No. 290,906, granted to me December 25, 1883. Such a fastener is adapted to be operated by one hand to open the bag by the action on the knobs of the thumb and forefinger, which action first springs them apart and then separates the two parts of the frame with one continuous movement of the thumb and forefinger. While this form of fastener is very convenient for use and easy to manipulate, it does not provide a positive catch for the mouth of the bag, the spring of the frame being depended upon to hold the parts of the frame together by the knobs as they pass by one another, and the frictional contact of the knobs is liable to be overcome when the frame is subjected to sudden shocks, thus allowing the bag to open.

This invention has for its object to make a fastener for bags, satchels, purses, &c., which, while embodying the advantageous capability of being manipulated by one hand, will afford a perfectly secure lock-fastening, and also to improve and simplify the construction of spring-catches for bags, &c., and at the same time add to the finished appearance of the frames. To this end each side or part of the frame has projecting upwardly from it a knob or handle, which knobs or handles are about in line with one another when the frame is closed. One of these knobs or handles may be firmly secured to its side of the frame, and the other one so connected to the other side of the frame as to be movable thereon, so as to release a spring-catch carried by one side of the frame and arranged to catch into a suitable notch or opening in the other side when the frame is closed. This spring-catch holds the parts of the frame securely and positively

together, and must be released from its notch before they can be separated, which is accomplished by pressing the two knobs apart by the thumb and one of the fingers or other parts of one hand. This manipulation of the knobs or handles by one hand first moves back the movable knob or handle, and so releases the spring-catch, and then further separates the knobs and the parts of the frame to open the mouth of the bag. Both of the projecting knobs may be movable on their respective sides of the frame and constructed to release the spring-catch, both knobs assisting in such operation; or independent catches may be employed and actuated separately by the knobs.

The improvement in spring-catches consists in forming the spring integral with a strip of metal secured to and surrounding one of the sides of the frame and acting as a cover to inclose the opening of the two sides of the frame when they are closed. The spring is arranged longitudinally in relation to the bag-frame, and is formed by making two longitudinal cuts in the auxiliary strip, joined at one of their ends by a transverse cut, the piece embraced by said cuts being bent so as to be above the surface of the strip. This auxiliary strip replaces the base-plate of the lock, the box or cover of the lock being secured directly to it over the spring.

Various kinds of spring-catches for bags may be used with and operated by the movable handle or handles, as will now be fully described, reference being had to the accompanying drawings, in which—

Figure 1, Sheet 1, is a front view of a bag-frame closed, showing my improved fastener applied thereto, in which one of the operating-handles is movable and the other one fixed. Fig. 2, Sheet 1, is a plan view of the same, partly open. Fig. 3, Sheet 1, is a side view, also partly open. Fig. 4, Sheet 1, is a longitudinal central section of the fastener closed, on a slightly enlarged scale. Fig. 5, Sheet 1, is a transverse section on the line xx , Fig. 4. Figs. 6, 7, 8, 9, and 10, Sheet 2, are views corresponding to Figs. 1, 2, 3, 4, and 5, Sheet 1, showing a modification in the construction of the spring-catch. Fig. 11, Sheet 2, is a longitudinal section of another modification in which only one of the handles is

movable. Fig. 12, Sheet 2, is a plan view of the same. Fig. 13, Sheet 2, is a plan view, partly in section, of a fastener in which both handles are movable. Fig. 14, Sheet 2, is a section of the same on the line yy' . Fig. 15, Sheet 2, is a plan view of a modification in which both handles are movable, working two independent catches; and Fig. 16, Sheet 2, is a section of the same on the line zz' .

- 10 My improved fastener is adapted to be applied to metal frames of any form of cross-section. In Figs. 1 to 5 an angle-frame, a and a' , is shown, the parts of which are pivoted together in the usual manner, and an auxiliary strip of metal, b , of a width equal to both parts of the frame, is secured to them by their connecting-pivots, and to the part a , the inner edge of which it overlaps and covers the part a' when the frame is closed, thus hiding any 15 imperfections in the meeting edges of the parts a and a' , and imparting to the two sides of the frame a uniform appearance. This covering-strip b acts as a base-plate for the lock, and the spring c is integral therewith and is 20 formed longitudinally in this strip b by being cut on three sides and bent up at the fourth side or one of its ends above the surface of the strip b . This spring c is provided with a downwardly-projecting tongue, c' , formed by a portion 25 of its metal being cut and bent from its central part. The box d incloses the spring c and is secured at its ends to the strip b by means of rivets, which also pass through the flange of the frame a , thereby securing all the 30 parts rigidly together. Before the box d is secured in position the lifting-plate e is placed under the free end of the spring c . This plate e has an arm, e' , bent at right angles to it, which projects upwardly through a slot in the 35 box d , and to the top of this arm is secured the knob or handle e'' . This arm e' has sufficient play in the slot in the box to allow the plate e to rock under the spring and raise it when the knob or handle e'' is forced over. 40 On the other part, a' , of the frame is secured by means of rivets the plate f , having a hasp, f' , projecting over the top of the frame, and so located as to enter an opening in the box d and pass under the spring c , whose projecting 45 tongue c' enters the opening or slot in the hasp f' , and so holds the two parts a and a' of the bag-frame together, said fastening being very secure by reason of the hasp lying between the spring c and the base plate or strip b . The 50 hasp-plate f has an extension, f'' , which projects over the top of the frame, and to which is secured the handle g , arranged to be in line with the movable handle e'' when the frame is closed. 55 It will be observed that this fastener is adapted to be released, and the mouth of the bag to which it is applied opened by one continuous operation of the thumb and forefinger or other parts of one hand, by bearing in opposite directions on the handles e'' and g , as shown by the dotted lines representing a hand 60 in Figs. 1 and 3. The first action moves the

handle e'' on the part a of the frame, thereby tilting the lifting-plate e , which vertically lifts the free end of the spring c until its tongue c' 70 clears the top of the hasp f' . Further pressure in opposite directions on the handles e'' and g separates the parts a and a' , as clearly shown in Fig. 3.

In the modifications shown in Figs. 6 to 10 75 two similarly-formed boxes, h and h' , are respectively secured to the parts a and a' of the frame, which are here shown as being cylindrical in form and without the covering-strip b . In the box h is pivoted the lifting-plate i , 80 having a projection, i' , arranged under an opening in the top of the box, and a stem projecting up through a slot in the top of the box, to which stem is secured the knob or handle i'' ; and on the top of the box h' is secured the 85 spring j and the knob or handle j' , the spring j being longitudinally arranged and provided at its free end with a projection, j'' , which falls into the opening in the box h when the bag is 90 closed. The spring j is first released when the fastener is manipulated, as before described, by the knob i'' moving over, and so causing the projection i' on the plate i to push the projection j'' of the spring out of the opening in 95 the top of the box h .

Figs. 11 and 12 show a modification, in which a longitudinally-sliding bolt, k , fitted in the box l , secured to one part of the frame, is caused by its spring k' to engage in an opening in the end of the box l , secured to the other part of the frame. A stationary knob or handle, m , is secured to the box l , and a movable knob or handle, m' , to the box l . This movable knob or handle m' is secured to the cam-plate n , pivoted to the top of the box l at n' , 100 which plate n , by means of a cam-slot therein, engages a pin, k'' , projecting from the sliding bolt k up through a longitudinal slot in the top of the box l , so that when the handle m' is pressed back the bolt k is withdrawn from 105 the opening in the box l and the bag, &c., 110 opened, as before described.

When it is desired to have both of the knobs or handles movable, and arranged to operate a positive catch, according to my invention, 115 the plan shown at Figs. 13 and 14 may be adopted. In these views the boxes o and o' , secured respectively to the parts a and a' of the frame, have centrally pivoted in them the rocking plates p and q , each of which is provided with a projection, respectively, p' and q' , which catch over or into notches q'' and p'' , 120 formed in q and p , after passing through openings in the approaching corners of the boxes, as the bag is closed, thus forming a double 125 lock, to release which each of the knobs or handles p'' q'' , secured respectively to the rocking plates p and q , has only to be moved a small distance. These plates p and q may be 130 in the same plane. In Fig. 14 they are put in different planes to more clearly show their construction, and they are actuated by springs r and r' .

In Figs. 15 and 16 each of the knobs s and t

actuates by being secured to an independent catch, which catches are composed of the plates s' t' , pivoted in their respective boxes, s^2 and t^2 , and having their free ends bent down, so as to engage in slots or openings formed in the parts of the frame opposite to that to which their holding-boxes s^2 and t^2 are respectively secured; they being held down by springs placed between their upper sides and the tops 10 of their respective boxes.

Having now described the nature of my invention and several methods by which it can be practically applied, I do not wish to limit myself to any particular construction in putting my invention into practice; but 15

What I claim, and desire to secure by Letters Patent, is—

1. In a fastener for bags, &c., in combination, the two parts of a hinged frame, a positive 20 spring lock or catch for securing the two parts of the frame together, and two similar knobs or handles, one attached to each part of the frame and connected to the spring-catch, so arranged when the bag is closed as to be manipulated by one hand, and by which the spring catch or lock is first released and the parts of the frame then separated by one continuous motion applied to the knobs or handles, substantially as set forth.

2. In a fastener for bags, &c., in combination, a spring-catch and a movable lifting-plate provided with an upwardly-projecting knob or handle carried by one part of the frame, and a hasp-plate and upwardly-projecting knob or handle secured to the other part of the frame, substantially as set forth.

3. In a fastener for bags, &c., a vertically-moving spring-catch secured at one end to one part of the frame, and a tilting lifting-plate

for raising the same, provided with an upwardly-projecting knob or handle, in combination with a projecting knob or handle secured to the other part of the frame, arranged to be in line with the other knob or handle when the bag is closed, and a hasp arranged 45 to engage the spring-catch, substantially as and for the purpose set forth.

4. In a fastener for bags, &c., in combination, a lock secured to one part of the frame and composed of a base-plate covering the top 50 and sides of the same, said base-plate having a spring-catch integral therewith, a lifting-plate located under the free end of the spring and having an upwardly-projecting arm, a box inclosing said spring and lifting-plate, and a hasp and projecting knob or handle secured to the other part of the frame, substantially as set forth.

5. In combination, the spring-catch c , the lifting-plate e , provided with the knob or handle e' , the inclosing box d , the hasp f' , and the knob or handle g , substantially as and for the purpose set forth.

6. In combination, the bag-frame a a' , the covering-strip b , provided with the spring- 65 catch c , integral therewith, and the hasp f' , and means, substantially as described, for raising the spring-catch and separating the two parts of the frame, as and for the purpose set forth.

In testimony whereof I have hereunto set my hand, at New York, county and State of New York, this 24th day of January, 1885.

JOHN MENAHAN.
